UNITED STATES PATENT OFFICE.

GEORGE E. ADAMS, OF NEW BRITAIN, CONNECTICUT.

DESIGN FOR A BODY PORTION AND BACK-STRAP CONNECTION FOR SUSPENDERS.

SPECIFICATION forming part of Design No. 35,297, dated November 19, 1901.

Application filed May 1, 1901. Serial No. 58,888. Term of patent 14 years.

To all whom it may concern:

Be it known that I, GEORGE E. ADAMS, of New Britain, in the county of Hartford and State of Connecticut, have invented and produced a new and original Design for a Body Portion and Back-Strap Connection for Suspenders, of which the following is a specification, reference being had to the accompanying drawing, forming a part thereof.

The accompanying drawing is an elevation of the body portion and back-strap connection of a pair of suspenders embodying the present design.

As shown in the drawing, the leading or material features of the present design consist of the single-length straps B, having the

two separate loops A, with the cross-stitching D arranged centrally and extending longitudinally throughout the straps above the loops A, and the back-strap connection E, 20 having eyes C encircling the loops A. The loops of the body portion have an interlaced effect, as shown.

What I claim is—

The design for a body portion and back-strap connection for suspenders; substantially as shown and described.

GEORGE E. ADAMS.
